(57) **CLAIM**

The ornamental design for a flowtube gauge scale, as shown and described.

DESCRIPTION

FIG. 1 is a front view of a flowtube gauge scale according to a first embodiment of the present disclosure;

FIG. 2 is a back view of the flowtube gauge scale of FIG. 1; FIG. 3 is a first side view of the flowtube gauge scale of FIG. 1;

FIG. 4 is a second side view of the flowtube gauge scale of FIG. 1;

FIG. 5 is a top view of the flowtube gauge scale of FIG. 1; FIG. 6 is a bottom view of the flowtube gauge scale of FIG. 1;

FIG. 7 is a front view of a flowtube gauge scale according to a second embodiment of the present disclosure;

FIG. 8 is a back view of the flowtube gauge scale of FIG. 7; FIG. 9 is a first side view of the flowtube gauge scale of FIG. 7;

FIG. 10 is a second side view of the flowtube gauge scale of FIG. 7;

FIG. 11 is a top view of the flowtube gauge scale of FIG. 7; and,

FIG. 12 is a bottom view of the flowtube gauge scale of FIG. 7.

Any portions shown using dashed lines are for illustrative purposes only and form no part of the claimed design.
